ATTORNEY.

UNITED STATES PATENT OFFICE

WILLIAM V. VAN ETEN, OF BELLINGHAM, WASHINGTON

MONKEY WRENCH

Application filed July 19, 1928. Serial No. 293,889.

My invention relates to improvements in monkey wrenches and has for an object to provide a wrench in which the desired adjustment of the wrench jaws may be made by the hand holding the wrench quickly while said jaws are in proximity to the work.

Another object of my improvement is to provide a quick-setting wrench adjustable to small differences.

Another object of my improvement is to provide a design for the holding mechanism of a quick-setting wrench which promotes strength and ease of operation.

Another object of my improvement is to provide a wrench the loose jaw of which is movable by gravity or by momentum toward other positions thereof and engageable in a desired position during said movements.

Other objects of my improvement will appear as the description proceeds.

The mechanism by which I attain these and other objects of my improvement is illustrated in the accompanying sheet of drawings in which Figure 1 is a front elevation of an offset-handle wrench with my holding and adjusting mechanism in place thereon, Fig. 2 is an edge elevation of Fig. 1 with the handle broken away, Fig. 3 is the rear elevation of Fig. 1 with the handle broken away and Fig. 4 is a cross section of Fig. 1 on the line 4—4 thereof.

Similar characters refer to similar parts throughout.

With more particular reference to the designated parts: A wrench having handle 5 and fixed jaw 6 has a transverse guide slot 7 extended entirely across the head of the wrench including an opening through the fixed jaw, and on one wall of said slot is guide rib 8. Rectangular opening 9 in said head intersects slot 7 and extends into the shank beneath said slot. In the front and back walls of the wrench head and tributary to slot 7 the corners of opening 9 are extended in notches 10, 10.

Movable jaw 11 has arm 12 integral therewith and mounted for reciprocation in slide-way 7 with slot 13 therein engaged with rib guide 8.

The lower edge of arm 12 slants upward

toward the rear and has a rack with transverse teeth 14 thereon.

A pin having thumb head 15 is fastened in the front side of arm 12 and enters notches 10, 10 as jaw 11 reciprocates; the bottoms of said notches serving as stops to said pin to limit the movement of said jaw from its dotted-line position at 11' to its dotted-line position at 11''.

Tumbler 16 is pivoted to oscillate in opening 9 on pin 17 which is extended through a hole in the wrench head parallel with guide-way 7. Tumbler 16 has thumb rib 18 protruding from the front wall and the lower part a16 of said tumbler is of larger diameter than the upper part thereof at b16, said lower part being eccentric with pin 17. Flat spring 19 is fastened to the handle by screw 20 and bears on the eccentric part a16 of the tumbler beneath rib 18 where it is smallest when said tumbler is in its full-line position. But when the tumbler is turned on pin 17 to its dotted-line position at 16' spring 19 is flexed thereby and moved to 19'. Thus it is clear that said spring tends to turn the tumbler in a reverse direction. A rack composed of teeth 21 is integral with the upper wall of tumbler 16 and slants upward from its smaller diameter at b16 to engage with teeth 14 of the rack on arm 12.

When tumbler 16 is in its full-line position teeth 21 are fully engaged with teeth 14 and their bearing thereon is maintained by pressure from spring 19; but when the tumbler is moved to its dotted position at 16', with rib 18 at 18', the teeth have moved to their dotted-line position at 21' entirely out of engagement with teeth 14 of arm 12. As stated, when tumbler 16 is in the said dotted position spring 19 is flexed to its dotted position at 19' and reacts most strongly to return the tumbler to its full-line position with teeth 21 engaged with teeth 14. From which it is evident that with the tumbler in its full-line position jaw arm 12 is retained by the tumbler from movement, while with said tumbler in its dotted position said arm is free from engagement with the tumbler and jaw 11 may be moved as desired to any position between its extreme limits at 11' and 11''.

When the wrench handle 5 is held in the right hand of an operative his thumb of that hand may bear upon rib 18 and move it upward against the reaction of spring 19, thus 5 setting free loose jaw 11 which may then be set in a desired position in adjustment either against the work or free therefrom; and when said thumb pressure is released from rib 18 spring 19 will react to return the tumbler to 10 engagement with the jaw arm and said loose jaw will be retained in its adjusted position relative to fixed jaw 6.

While the operative's thumb is bearing on rib 18 it is within reach of cross hatched pin 15 head 15 and, when said rib is at 18', this pin may be moved by the thumb as said thumb slides on the rib which is made to extend the entire length of the tumbler for this purpose. Thus, it is clear that with one hand alone an 20 operative may hold, set and turn my wrench in desired directions to suit the nature of the work being performed.

The eccentric part of the tumbler is exposed at the rear of the wrench also and jaw 25 11 may be released by pressure from a finger applied thereto.

A useful feature of my wrench is made possible by the described location of tumbler 16 in the wrench head whereby during periods 30 when tumbler engagement with the loose jaw is withheld by thumb pressure on rib 18, the loose jaw may be caused to gravitate either toward or from the fixed jaw by a twist of the wrist of the operative holding the wrench 35 handle and when the loose jaw reaches the desired new location it may be caught and held therein by the tumbler released from thumb pressure on rib 18. The same relative movement of the loose jaw may be caused by a 40 sudden lateral swing of the wrench handle while held by the operative and said loose jaw may be caught and held by the released tumbler as before.

The size of teeth 14 and 21 shown is for the 45 benefit of the illustration, in practice they are made smaller to provide for small adjustments of the loose jaw.

The shape of handle 5 as well as the shape and relative proportions of other parts of the 50 wrench as illustrated may be changed to suit the nature of the work to be performed or the preferences of operatives. Such other shapes and proportions which depend for their usefulness on the principles of my invention are 55 also within its purview.

Having thus disclosed my invention, what I claim as new therein and desire to secure by Letters Patent is,—

In an adjustable wrench, a fixed jaw fastened to a wrench head, said wrench head having a slideway opening therethrough from edge to edge and a tumbler opening therethrough from side to side thereof intersecting said slideway opening, a loose jaw, an 60 arm fastened to said loose jaw at right angles 65

with the work face thereof, engageable in said slideway for reciprocation and having a beveled outer edge with a toothed rack thereon, a thumb-hold pin fastened in said arm protruding from one side thereof through said intersection of said tumbler opening and said slideway opening, a bearing pin extended through said head across said tumbler opening parallel with said slideway, a tumbler mounted eccentrically on said bearing pin in 70 said tumbler opening for oscillation and having a toothed rack thereon engageable with and disengageable from said arm rack by the oscillation of said tumbler on said bearing pin, a rib on the exposed surface of the tumbler lengthwise thereof adjacent the said thumb-hold pin to provide a thumb hold, a wrench handle fastened to said head, and a flat spring fastened to said handle and bearing on said eccentric tumbler to react and 75 cause the same to return to engagement with said loose jaw arm.
